DESIGN FOR A NEGLIGEE

Violet Giovagnoni, New York, N. Y.

Substituted for abandoned application Serial No.
D. 136,110, January 13, 1947. This application
January 13, 1948, Serial No. 143,714

Term of patent 3½ years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee, of which the following is a specification, reference being had to the accompanying drawing, forming part thereof. This application is a substitute for my abandoned application D. 136,110, filed January 13, 1947.

Fig. 1 is a front view of a negligee showing my design, and

Fig. 2 is the rear view thereof.

The characteristic feature of my design resides in the combination on the negligee disclosed of the specific embroidered lace trim arranged on the collar and sleeves, as shown.

I claim:
The ornamental design for a negligee, substantially as shown and described.

VIOLET GIOVAGNONI.
